Fig. 2.

Inventor

Fig. 3. Charles H. Miller.

By *N. L. Gollamer* Attorney

UNITED STATES PATENT OFFICE.

CHARLES H. MILLER, OF LINEVILLE, IOWA.

ELEVATOR SAFETY DEVICE.

Application filed April 8, 1922. Serial No. 550,601.

To all whom it may concern:

Be it known that I, CHARLES H. MILLER, a citizen of the United States, residing in Lineville, in the county of Wayne and State 5 of Iowa, have invented certain new and useful Improvements in Elevator Safety Devices, of which the following is a specification.

This invention relates to elevators, and 10 more especially to car brakes and catches, door controlled.

Its objects are several, to wit: First to lock every shaft door closed except that opposite the car; second, to lock the car 15 against movement while any door is open; third, to coordinate the first two objects; and fourth, to adapt the invention to various shafts, elevators, doors, and latches.

The invention consists first, in means at 20 each landing for locking the door-latch (and therefore the door) against being opened save when the car is opposite this landing; second, in an obstruction in the well or shaft for locking the car against movement in either direction and holding it at 25 any landing while that door is open; third, in a cam in the shaft engaged by the car when opposite a landing to release the lock for the door-latch; fourth, in means on the 30 door whereby its closing releases the car-lock; and fifth, in the details of construction whereby the several parts are adaptable to a variety of cases.

The elevator well may be but a hole, substantially vertical, passing a plurality of stations; doubtless it will have guides for the car, and probably it will be a shaft more or less housed in, especially at the floors or landings. Here will occur doors or 35 gates, swinging or sliding, to right or to left; and each will have one or more latches engaging appropriate keepers to hold it closed, and a latch-bar accessible from inside or outside the shaft so that the operator can unlatch such door. The elevator 40 may be a mere platform, a car, or a more elaborate cage; it may itself have a door, although that is not to be considered herein; and its structure, size, motive power, and 45 controls are immaterial to the invention.

With the above understanding of the terminology to be employed in the following specification and claims, it is clear that the drawings need not elaborate details which

are unessential. Referring to the accompanying sheets—

Fig. 1 is a perspective view from within the shaft with the car absent and the door closed at a landing, showing how its latch-bar is locked.

Fig. 2 is a horizontal section on the line 2—2 of Fig. 1 showing how the closing of the door automatically throws the car-lock out of action.

Fig. 3 is an elevation, viewed in the direction of the arrow 3 of Fig. 1, the dot-and-dash lines indicating the car platform at the landing and a block on such platform which releases the latch-lock. The door is here partly opened, and it has released the 70 car-lock which now engages said block.

Fig. 4 is a horizontal section on the line 4—4 of Fig. 3, taken just above the floor level.

At each landing or floor F the elevator shaft or well may be enclosed by a wall W secured to corner guides G. In this wall is an opening closed by a door D and possibly having its door casing C—all as best seen in Fig. 2. The elevator is herein shown as 75 a mere platform E, which in Fig. 3 stands opposite the landing at the floor F, and for purposes of illustration this platform is shown as having an element such as a corner block 1 which moves up and down 80 on the guide G. If the elevator were a car or cage, its corner post might serve 85 as such element. Each door may slide or swing; if the former, it moves as indicated by the double arrow 5; if the latter, its free edge moves on the arc 6 in Fig. 2. Said edge by preference has a beveled wear-plate 7 at its lower corner closing across a right-angular notch 8 in the edge of the flooring, for a purpose yet to appear.

Sliding vertically in suitable guides on the door is a latch bar 11 which is shown in Fig. 1 as having a latch 12 notched as at 13 to engage a keeper 14 in the guide G or 100 the casing C or between them; and a second latch is indicated at 12'. It will be understood that several such latches may be used if desired, to hold the door securely closed and preserve the continuity of the shaft wall, and that latches of different type may be employed, especially if the door swings rather than slides. The lower end of the 105

bar 11 is shown as deflected inward as at 15, and then carried down and hooked outward as at 16 above the floor F. This illustration and description applies to one form of latch and its bar, although I do not wish to be limited thereto; it is essential that the bar 11 be lifted to release the latch, and openings in the door and handholds 17 on the bar may be provided so that it may be raised by an operator within the shaft or upon the floor. Manifestly, if some element stood over the hook 16, it would lock the bar against rise, prevent disengagement of the latch from its keeper and therefore hold the door locked.

Hinged within a recess 20 which is cut in the inner face of the guide G above and below the line of the floor, is a cam plate 21 swung normally outward into the well or shaft by a spring 22 but adapted to be pressed back out of active position and housed in said recess by the edge of the elevator platform, or, in the present instance, by the block 1 as shown in Fig. 3. Projecting rigidly from its hinged edge is an upright lip 23 whose upper extremity is hooked toward the door as at 26. (In the drawings this lip is shown with another and similar hook 25 at its lower end, but when the cam is reversed as for use where the door closes in the opposite direction, this hook comes uppermost as will be understood. The lip is made with both hooks to permit the cam element to be applied either way.) When the hook 26 passes over the hook 16, the latch-bar 11 is locked; when the car comes opposite the platform, the cam plate is pressed into the recess 20, the hooks are disengaged, and the door may be manually unlatched and opened.

Hingedly mounted within the same recess 20 is a car lock, here shown as comprising an upright shaft 31 having top and bottom right-angular fingers 32 spaced so as to swing over and under the block 1 and yet leave the car some little latitude of movement at the landing. It will be clear, however, that said fingers could be spaced so as to swing above and below the corner post of an elevator cage, which post in that case would become the element herein referred to as "block." A spring 33 throws these fingers normally outward into the well where they form an obstruction to the movement of the car, but they may be pressed back out of active position and housed in said recess. I find it convenient to make the shaft 31 a bearing for spaced hinge-eyes 27 on the cam plate, and to mount the shaft itself in other eyes or bearings 37 in the recess, so that the cam plate and car lock are concentrically pivoted or hinged while they move independently of each other. Projecting rigidly from said shaft is an upright lip 38 shorter than the lip 23 and spaced from its hooks 25 and

26 by the two hinge-eyes 27, and this lip 38 constitutes an inclined lever standing within the notch 8 in the landing floor F and struck by the wear plate 7 on the door as the latter closes; this action therefore presses the fingers 32 into the recess 20, and the car is free to move up or down. (The spring 33 is here shown in the form of a small helix attached at one end to the lever or lip 38 which is pierced with holes 39 for this purpose, and is led thence under the floor F and attached at its other end thereto; but any form of spring will answer. The holes 39 are here duplicated so that the car lock can be reversed and employed in the opposite corner of the shaft when the door opens in the opposite direction, but this is a detail.)

This invention is designed especially for use in a self-propelled manlift; when applied to an elevator having an attendant, there will be no openings in the doors for passengers at the several landings as the handholds 17 will be operated by the attendant only. Let us assume the manlift applied to domestic purposes or used in a grain elevator. The car stands normally at the level of the lower floor, and all doors are closed and latched, the latch bar of the lower door only being unlocked because the car by its presence there depresses the cam plate. A would-be passenger approaches and unlatches and opens this door; immediately the U-shaped car lock swings inward, and the car is locked and cannot be moved until the door is again closed. He enters and closes the door after him, and the car is unlocked; he now ascends to some other floor, and the cam plate swings inward to lock the latch bar of the lower door so that no one can open it.

As the car passes each landing the block depresses the cam plate and throws the latch lock out of active position; reaching the floor desired, the passenger unlatches and opens the door there (locking the car) and emerges. The car cannot now move until this door is closed again, and it cannot be caused to move except by a passenger standing on the platform of the car within the well—conditions and limitations which are ideal in a lift of this type.

What I claim as new is:

1. In an elevator safety device, the combination with a door at each landing, a latch therefor, and a hook connected with the latch; of an element in the well having a hook, means for holding the hooks engaged when the door is closed and latched, means actuated mechanically when the car is opposite the landing for disengaging said hooks, and means for permitting the manual disengagement of the latch from its keeper when said hooks are disengaged.

2. In an elevator safety device, the combination with a door at each landing, a

5 manual latch therefor, and a hook connected with the latch, of an element in the well having a hook, means for holding said hooks engaged when the door is closed and latched, and means actuated by the car when opposite the landing for disengaging said hooks.

10 3. In an elevator safety device, the combination with a door at each landing, its latch, and a latch bar having a handhold and a hook; of an element mounted in the well and normally engaging said hook to lock said bar, and means actuated by the car when opposite the landing to move said element out of engagement with said hook.

15 4. In an elevator safety device, the combination with a door at each landing, its latch, and a vertically moving latch bar having a hook; of a cam hinged in position to be depressed automatically by the car when opposite the landing, a spring projecting the cam normally into the well, a lip extending rigidly from the cam, and a hook on the lip for engaging that on the bar when the cam is projected but disengaging it when the cam 25 is depressed.

5. Claim 4 plus: Means for permitting the manual lifting of the latch bar when said hooks are disengaged, thereby unlatching the door.

30 6. In an elevator safety device, the combination with a door at each landing, a manual latch on the door, mechanism for locking the latch closed, and means for throwing said mechanism out of action when the car is opposite the landing; of mechanism for locking the car opposite each landing, and means for throwing the last-named mechanism out of action by the closing of the door.

35 40 7. Claim 6 plus: Both said mechanisms being yieldingly projected into the well, and a block on the car which engages the latch-

locking mechanism and is engaged by the car-locking mechanism.

8. In an elevator safety device, the combination with a door at each landing, a latch thereon for engaging a keeper, an upright latch bar having a hook at its lower end, and a wear plate at the lower front corner of the door; of a door lock and a car lock opposite the landing, a hook on the door lock for engaging that on said latch bar, a release lever on the car lock for engagement by said wear plate when the door closes, and means on the car for disengaging said hooks when the car comes opposite the landing.

9. In an elevator safety device, the combination with a door at each landing, a latch thereon for engaging a keeper, an upright latch bar having a hook, and a wear plate 60 on the door; of a cam plate hinged in the well wall at each landing and having a hook for engaging that on the latch bar, a U-shaped car lock also hinged in the well wall 65 at each landing and having a lever for engagement by said wear plate, and means for swinging said cam and car lock normally into the path of the car.

10. Claim 9 plus: The means being yieldable, and a block on the car adapted to depress the cam plate and disengage said hooks and to be received between the fingers of the U-shaped car lock.

11. Claim 9 plus: The means being yieldable, and a block on the car adapted to depress the cam plate and disengage said hooks and to be received between the fingers of the U-shaped car lock, said cam plate and lock being concentrically hinged in and adapted to be housed within a recess in said 75 wall.

In testimony whereof I affix my signature.

CHARLES H. MILLER.
